UNITED STATES PATENT OFFICE.

FREDERICK C. ROBERTSON, OF SPOKANE, WASHINGTON, ASSIGNOR, BY MESNE ASSIGNMENTS, TO RUBBER-METAL HORSE FOOTWEAR, INC., OF BUFFALO, NEW YORK, A CORPORATION OF NEW YORK.

HORSESHOE.

Application filed September 18, 1920. Serial No. 411,156.

To all whom it may concern:

Be it known that I, FREDERICK CONRAD ROBERTSON, a citizen of the United States, and a resident of Spokane, in the county of 5 Spokane and State of Washington, have invented certain new and useful Improvements in Horseshoes, of which the following is a specification.

The present invention relates generally 10 to horseshoes, and more particularly to a cushioned horseshoe of composite structure.

The object of the invention is to provide 15 a composite horseshoe of this character in which the force of impact and the tearing and major abrasive forces acting along the 20 shoe are received by a metallic element and thereby prevented from breaking down the structure of the cushioning element, and in which the cushioning element is most highly effective to absorb the stresses set up by the 25 forces acting upon the metallic element and to receive and absorb the forces not effective to deteriorate the cushioning element.

Another object of the invention is to provide 30 a horseshoe of this character of simple, durable and lightweight construction, reliable and efficient in practice, and easy and inexpensive to manufacture.

Other objects and advantages reside in the 35 certain novel features of construction, arrangement and combination of parts which will be hereinafter more fully described and particularly pointed out in the appended claims, reference being had to the accompanying drawings forming part of this specification, and in which—

Figure 1 is an elevational view of the tread surface of the shoe;

Fig. 2 is a transverse horizontal section 40 thereof;

Fig. 3 is a transverse vertical section on the line 3—3 of Fig. 1;

Fig. 4 is a transverse vertical section on the line 4—4 of Fig. 2;

Fig. 5 is a transverse vertical section on the line 5—5 of Fig. 2;

Fig. 6 is a detail perspective view of the heel of the shoe;

Fig. 7 is a plan view of a form of my invention embodying a pad;

Fig. 8 is a transverse sectional view thereof on the line 8—8 of Fig. 7;

Fig. 9 is a side elevational view;

Fig. 10 is a plan view, parts being broken

away for the sake of illustration, and the metallic element being removed, of a form of my invention of sectional construction;

Fig. 11 is a sectional view thereof on the line 11—11 of Fig. 10;

Fig. 12 is a side elevational view; 60

Fig. 13 is a plan view of a modified form of cushioning member;

Fig. 14 is an end view of the structure shown in Fig. 13;

Fig. 15 is a plan view of a horseshoe 65 adapted to accommodate the cushioning member shown in Fig. 13;

Fig. 16 is an edge view of the horseshoe shown in Fig. 15;

Fig. 17 is an assembled view of a complete horseshoe, cushion, and pad embodying the invention; 70

Fig. 18 is a sectional view through Fig. 17 on line 18—18; and

Fig. 19 is a sectional view through Fig. 17 75 on line 19—19.

Referring to the drawings, it will be seen that the invention in all of its embodiments contemplates a cushioning element indicated generally at C and a metallic element indicated generally at M.

In the embodiment of the invention shown in Figs. 1 to 6, the cushioning element comprises a body of cushioning material, such as vulcanized rubber, and includes a sheet-like portion 10 arranged to bear against the hoof of the horse. The body also includes a sheet-like portion 11 which constitutes the inner portion of the tread surface of the shoe, and an intermediate portion 12 integral with the portions 10 and 11 and connecting the same. 85

The metallic element consists of a plate 13 of horseshoe form embedded in the vulcanized rubber of the body of the shoe to lie between the portions 10 and 11 and abut the portion 12 of the cushioning element. The plate 13 is provided with an integral marginal flange 14 which extends entirely around 90

the outer marginal edge of the shoe and also around the heel of the shoe, as indicated at 100 15 in Figs. 1 and 2. The outer surface 14^a of the flange is arranged to constitute the outer marginal portion of the tread surface of the shoe.

The metallic plate 13 is provided with a 105 plurality of key openings 16 through which the vulcanized rubber extends to more positively associate the metallic and cushioning

elements. The shoe is also provided with nail holes 17 which, as clearly shown in the drawings, extend through the flange 14 and the underlying portion 10 of the rubber.

5 The surface of the rubber constituting a portion of the tread surface is suitably formed to prevent slipping and for this purpose is provided with a plurality of vacuum or suction cups 18 and a plurality of serrations or similar devices 19. The planes of the highest points of the anti-slipping devices, however, are all co-incident or below, preferably co-incident, with the tread surface 14^a of the flange 14. The tread surface 10 of the flange and the tread surface of the rubber are thus in general co-planar and together make up the tread surface of the shoe.

In use, the tread surface 14^a of the flange 14 receives the impact and the major forces 20 incident to traction, as this surface 14^a extends entirely around the outer marginal edge of the shoe. The stresses set up in the flange 14 and the metallic plate 13 of which it forms a part are not, however, communicated to the hoof of the horse, but are absorbed by the cushioning material, mainly by the portion 10 thereof which underlies and is interposed between the flange 14 and its plate 13, and the hoof. Although the 30 surface 14^a of the metallic element receives the force of impact and the major abrasive and other forces incident to traction, the tread surface of the portion 11 of the vulcanized rubber comes into action almost simultaneously with or at least immediately after the impact and is effective to enhance the traction and thereby prevent slipping and to receive and absorb the minor forces 35 acting upon the shoe. The portion 11 of the cushioning material is strengthened and supported in its function by the metallic plate 13, and the cushioning action of the portion 11 is supplemented by a similar action of the portions 10 and 12.

40 It is to be noted that although the metallic element is firmly embedded in the vulcanized rubber constituting the body and is positively associated therewith by virtue of the extension of the rubber through the key 45 openings, the flange 14, in addition, is effective at the toe and heel and entirely around the shoe to prevent disassociation of the rubber or of any portion thereof from the metallic element, functioning in this respect as 50 a retaining ring to prevent tearing, splitting, or similar breakdown of the cushioning element which would otherwise be incident to traction.

55 In the embodiment of the invention shown in Figs. 7, 8 and 9, the cushioning element comprises a body of vulcanized rubber, and includes a sheet-like portion 20 which may bear directly against the hoof or which may be provided with a covering 21 of tough 60 fabric. The body also includes a portion 22

which, as before, constitutes the inner portion of the tread surface of the shoe. A pad 23 forms an integral part of the cushioning element and extends entirely across the heel of the shoe and centrally thereof, as clearly 70 shown in Fig. 7.

A metallic element 24 is provided, and consists of a plate of horseshoe form, embedded in the vulcanized rubber of the shoe and lies between the portions 20 and 22 75 thereof. The plate is provided with an integral marginal flange 25 which extends entirely around the outer marginal edge of the shoe, as shown in Fig. 7. The outer surface 25^a of the flange thus constitutes the outer 80 marginal portion of the tread surface of the shoe. The metallic plate is provided with a plurality of key openings 26 through which the vulcanized rubber of the cushioning element extends to positively associate the metallic and cushioning elements. The shoe is also provided with nail holes 27 which extend through the flange 25 and the underlying portion of the cushioning element.

The surfaces of the rubber and of the 90 metal constitute the tread and are suitably formed to prevent slipping, and the highest points of the rubber and of the metallic element lie in the same plane or else the highest points of the surface of the rubber lie below 95 the plane of the highest points of the surface of the metal. The tread surface of the flange and the tread surface of the rubber are thus in general coplanar and together make up the tread surface of the shoe. The rubber 100 provides also a pad which functions, as usual, to relieve strain on and rest the hoof of the horse.

The form of my invention shown in Figs. 10, 11 and 12 is, as shown, preferably embedded in a shoe of the pad type, such as 105 shown in Figs. 7, 8 and 9, but this form of my invention may be also embedded in shoes of the type shown in Figs. 1 to 6. This form of the invention includes a metallic 110 element and a cushioning element C, the cushioning element consisting of vulcanized rubber and the metallic element being constituted of any suitable metal. As clearly 115 shown in the drawing, the cushioning element is formed in general of two sections 28 and 29, which are formed by splitting the tipping of the shoe, as at 30. It is obvious 120 that the sections 28 and 29 may be flexed to vary the size of the shoe and that the metallic elements 31 of various sizes may, after the sections have been suitably flexed, be slipped over the sections to embrace and retain the same in position. When the shoe 125 is then secured to the hoof of the horse by the nails which extend through the nail holes of the metallic element and of the cushioning element the parts are positively maintained in assembled position. The cushioning 130 action of this embodiment of the invention

tion is in all respects similar to that of the other embodiments of the invention, as hereinabove described.

In Figs. 13 to 19 inclusive will be seen a modified form of the invention in which a horseshoe 32 is disclosed made in substantially the conventional form, but designed to receive the cushioning member 33, which may be made of rubber or other material, 10 said cushioning member having a thick inner section 34 and a comparatively thin flange or outer section 35 adapted to fit flatwise against the inner surface of the shoe 32. A pad 36 is also provided formed 15 with a heel 37 and a flat body 38 adapted to fit beneath the cushioning member 33 and to entirely cover the horse's hoof when in use. This construction may be made completely of rubber, or if desired may be made 20 from canvas or other stiffening material arranged therein, particularly in the heel member 37. After the parts have all been assembled as shown in Figs. 17 and 19 the ordinary horseshoe nails are forced through 25 the usual openings 39 through flange 35 and part of the body 38 of pad 36 and from thence into the horse's hoof. The usual nails in this manner not only hold 30 the completed shoe in place on the horse's foot but hold the various parts firmly together so they will act simultaneously and in a proper manner. It will be noted from Fig. 18 that part of the rubber cushion engages the ground, and the horseshoe 32 35 engages the ground adjacent the cushion while the horseshoe is continually cushioned by the flange 35 and part of the pad 36.

I claim:

1. A composite horseshoe, comprising a 40 body of cushioning material including a portion constituting the entire hoof-engaging face of the shoe, and a portion constituting the inner surface of the tread, and a metallic element consisting of a plate of 45 horseshoe form embedded in said cushioning material and provided with a relatively thick flange having a relatively wide ground-engaging surface extending entirely around the outer marginal edge of said 50 plate and constituting a wear surface and a substantial portion of the tread surface of the shoe, whereby said metallic element receives the force of impact and the major forces of traction and the cushioning ele-

ment absorbs the shocks incident to traction.

2. A composite horseshoe, comprising a body of cushioning material including a portion constituting the entire hoof-engaging face of the shoe and a portion constituting the inner surface of the tread, and a metallic element consisting of a plate of horseshoe form embedded in said cushioning material and provided with a relatively thick flange having a relatively wide ground-engaging surface co-planar with the inner surface of the tread constituted by the portion of the cushioning material and extending entirely around the outer marginal edge of said plate and constituting a wear surface and a substantial portion of the tread surface of the shoe, whereby said metallic element receives the force of impact and the major forces of traction and the cushioning element absorbs the shocks incident to the action of said forces.

3. A composite horseshoe, comprising a body of cushioning material including a sheet-like portion constituting the entire hoof-engaging surface of the shoe, a second sheet-like portion spaced from and substantially parallel to the first sheet-like portion and constituting the inner surface of the tread, and an intermediate portion connecting said sheet-like portions, and a metallic element consisting of a plate of horseshoe form, and arranged between and embedded in the sheet-like portions and provided with a relatively thick flange having a relatively wide ground-engaging surface extending entirely around the outer marginal edge of said plate and constituting a wear surface and a substantial portion of the tread surface of the shoe, whereby said metallic element receives the force of impact and the major forces of traction and the cushioning element absorbs the shocks incident to the action of these forces, the plate having key-openings extending therethrough, and the body of cushioning material having portions extending through the key-openings of the plate to enhance the organization of the metallic and cushioning element, said horseshoe having nail-holes extending through the flange of the metallic element and the underlying portion of the cushioning element.

FREDERICK C. ROBERTSON.
